DEVICE FOR RELEASEABLY SECURING
BRUSH STRIPS IN BRUSH ROLLSLouis E. Segesman, Canton, Ohio, assignor to
The Hoover Company, North Canton, Ohio, a
corporation of Ohio

Application September 16, 1948, Serial No. 49,579

5 Claims. (Cl. 15—183)

1

My present invention relates to the art of cleaning devices and more particularly to a brush mounting device particularly designed for use in the nozzle mouth of a suction cleaning apparatus.

It is an object of the present invention to provide a brush roll particularly adapted for suction cleaning devices which consists of a drum having rigidly attached and inset therein a bristle strip with the bristles projecting beyond the periphery of the drum, but in which the total length of the bristles is considerably less than the radial distance from their outer ends to the center of the drum.

It is a further particular object of the present invention to provide a brush roll or agitator construction in which a brush strip is mounted in a recess in the periphery of the roll and wedged therein by a simple, quickly detachable, light weight, inexpensive part.

It is a further object of the present invention to provide a brush roll having an L-shaped land formed therein in the corner of which is seated a brush strip and a wedging device detachably secured to one face of the L-shaped land serving to wedge the brush strip into position in the angle formed by the two legs of the L-shaped land.

Other objects and advantages of the invention will become apparent as the description proceeds when taken in connection with the accompanying drawing in which:

Figure 1 is an elevational view partly in section showing the preferred form of the invention;

Figure 2 is a sectional view taken along the lines 2—2 of Figure 1;

Figure 3 is a modified form of the invention shown in Figure 1 illustrating its application to a helical brush strip;

Figure 4 is a further modified form of the invention showing a modified form of an anchoring means for the brush strip;

Figure 5 is a transverse sectional view taken along the line 5—5 of Figure 4 and looking in the direction of the arrows.

Referring now to the drawing in detail and more particularly to Figure 1 thereof, there is shown an agitator roll particularly designed for use in the suction mouth of a suction cleaning device such as the arrangement illustrated in U. S. Letters Patent 1,907,692, issued to H. B. White, May 9, 1933.

The brush roll comprises a main body or drum portion 10 depressed in its center to form a pulley seat 11. The ends of the drum 10 each telescope over an enclosure and bearing seat 12 and abut

2

end flanges 13 thereon. Preferably the fit between the elements 12 and 10 is a frictional one, however spot welding or other additional securing means may be utilized if desired. Each element 12 includes a central bearing seat cup 14 in which is received the bearing structure 15 rotatably supporting the body structure 10 and the seat and bearing structure 12 upon a stationary shaft 16 which passes through and is journaled in the bearing structure 15. Suitable dust caps 17 are secured to the projecting ends of the shaft 16 to form a dust shield around the exposed faces of the bearing structures 15.

The brush roll body 10 is deformed on each side 15 of the pulley portion 11 to form brush receiving seats. This is accomplished by deforming the metal of the body 10 to form an L-shaped seat consisting of a short inwardly extending wall portion 18 which is substantially parallel to a radius of the drum 10 but offset to the right thereof as viewed in Figure 2. The short wall 18 joins a longer wall 19 which is normal to the wall 18 and to the radius to which the wall 18 is parallel thus forming a substantially L-shaped indentation 20 in the surface of the drum 10. The inner end of each of the seats formed by the walls 18 and 19 is separated from the ends of the pulley portion 11 by a slitting operation before the metal is deformed. The inner ends of the brush seats 25 are closed by wall plates 20 having the configuration of the brush seat in cross-section and provided with short forwardly extending tabs or tongues 21 which are spot welded to the upper faces of the surface 19 so as to close the inner ends of the brush seats. The outer ends of the brush seats are closed by the peripheral flange portion 13 of the bearing cup housing structure 12.

One or more slightly inwardly depending lances 22 are preferably formed in the wall 19 adjacent the point at which it joins the periphery of the drum 10 to form anchoring shoulders for a purpose to be described hereinafter.

A continuous brush strip consisting of bristles 24 and a channel-shaped metal backing 25 is 45 provided for use with the drum 10. The channel backing 25, see Figure 2, is seated in the angle formed by the junction of the walls 18 and 19. The brushes of this known type consist preferably of the type consisting of a plurality of bristles looped over a wire with the bight portions of the bristles and the wire lying within a metallic channel which is then pinched tightly against the bristles to bring the projecting portions of the bristles on the two sides of the wire 50 together and to anchor the whole assembly in the

metal backing. This type of construction may be made in the form of a continuous strip which is then cut to desired lengths as the strip is utilized. This type of strip is also made up in predetermined lengths with the end portions of the channel bent over to form closures at the ends of the individual brush strip. I contemplate using these and various other types of continuous strip brushes in my improved brush roll construction.

The base of the channel 25 is slightly bulbous due to the aforesaid pinching operation. For this reason the wall 18, though generally parallel to an offset radius of the roll body 10, is in the form of a flat S curve. This configuration of the wall 18 allows the flat bight portion of the channel to rest flat on wall 19 with one side of the bulbous base fitting snugly into the curved junction of walls 18 and 19. Also the wall 18 engages one upper side edge of the channel 25 to provide firm lateral support. The outer end of wall 18 is also curved into a junction with the cylindrical surface of the roll 10 to provide a rounded surface over which the bristles 24 may bend when brushing a surface undergoing cleaning.

The brush strip is secured in position upon the brush roll by a clamping plate 30 which is in the form of a very shallow channel in cross section and is provided with tabs or shoulders 31 which engage against the inwardly facing shoulders formed by the lancés 22 in the wall 19. The other edge of the channel 30 engages one side face of the metallic channel 25 above the bulbous base portion thereof to hold the brush structure firmly against the walls 18 and 19 at the angle formed by their junction point. The clamping strip 30 is secured in place and moved into tight wedging engagement with the channel 25 and shoulders 31 by means of a self-tapping screw 33 seated in a depression 34 formed in the strip 30. The self-tapping screw engages in a suitable opening 35 formed in the wall 19 to receive it. When the screw 33 is tightened the clamping plate 30 is drawn toward the wall 19 thus wedging the brush back 25 firmly against the supporting walls 18 and 19 at their junction point.

The foregoing assembly provides a construction by which an inexpensive continuous brush strip can readily be mounted in an agitator body with a single securing screw or bolt and can readily be removed requiring only a screw driver for that purpose. It is also to be noted that the brush strip extends the full length of the agitator on each side of the pulley portion 11 thereof out to the very end of the agitator body and substantially in contact with the end shield structure 12 so that the full length of the body structure 10 is an active brush bearing area and no securing means are necessary at the end of the brush strip.

As shown most clearly in Figure 2 it will be seen that the securing tongues 21 for the end closure plates 20 of the brush seats rest upon the plates 19 outwardly of the portions thereof which actually contact the brush backs 25 and that the clamping plates 30 overlie and seal the securing tongues from view when the apparatus is in assembled operating form.

In the form of the invention illustrated in Figure 1, the agitator roll is provided with one brush strip on each side of the pulley structure 11 displaced 180° from each other, however, other arrangements are within the purview of the invention and more than one brush strip may

be utilized on each end of the agitator if desired with various angular spacings with respect to each other. As shown in Figure 1, the brush roll structure is also provided with a helical rigid agitator bar 37 on each side thereof and spaced approximately 180° from the brush strip on the same side of the pulley therewith.

The form of the invention shown in Figure 3 is identical with that shown in Figures 1 and 2 except that the bristle strip, its supporting seat in the brush body 10, and its securing means are all formed on a helix having a pitch of approximately 11° in contrast to the straight bristle strips parallel to the axis of rotation of the brush roll body illustrated in Figures 1 and 2. In the Figure 3 form of the invention, the parts of the apparatus are given the same reference characters as the corresponding parts shown and described in connection with Figures 1 and 2 distinguished by the addition of a prime. The bristle strip 24', the securing plate 30', and the seat in the body 10' upon which these are secured are all formed on an approximately 11° helix. Other pitch helices are within the scope of the invention. The helix illustrated is one which has been found to be very satisfactory in practice.

In Figures 4 and 5, a third modification of the invention is illustrated which differs from the modifications of Figures 1 and 2 principally in the construction of the securing means for the brush bristle strip.

In this form of the invention the brush roll body structure 50 is provided with a central depressed portion forming a pulley 51 and is provided with an end bearing structure, not shown, which is identical to that shown in Figure 1. A portion of the periphery of the drum or body 50 is depressed to form an L-shaped brush strip seat comprising a slightly S-shaped wall 53 generally parallel to a radius of the drum or body 50 which meets a substantially flat longer wall portion 54 normal to the aforesaid radius. The slight S-shape of the wall 53 is designed to accommodate and engage the side face of a brush strip backing or base 55 which is identical with the brush strip construction 24 and 25 described in connection with Figures 1 and 2. The wall 54 is provided with a continuous depression 56 to form an abutting shoulder for a purpose to be described hereinafter. The depression 56 does not extend the full extent of the wall 54 between the end bearing structure and the pulley as will become more apparent later. The brush strip is secured in side abutting engagement with the wall 53 and in seating engagement with the wall 54 at their point of junction by a spring clamping strip 57 extending the major portion of the length of the brush strip but stopping short of the ends thereof as more clearly shown in Figure 4. The outer end of the spring strip 57 is turned over as indicated at 58 to abut the shoulder formed by the depression 56. The inner end of the spring 57 is provided with a plurality of spaced curved engaging tabs 59 which abut the outer side face of the backing strip 55 of the brush structure to provide a plurality of points at which the clamping action of the spring strip 57 is applied. A pair of self-tapping screws 60, which are similar to the screw 33 as described in connection with Figure 1, extend through the clamping spring 57 and are screwed into the wall 54. When the screws 60 are drawn up tightly the various contacting tabs 59 on the spring strip 57 are wedged into engagement with

the backing strip 55 which in turn wedges the brush strip into the angle between the walls 53 and 54 at their juncture providing a rigid and secure attachment between the brush strip and the brush roll body 50.

As shown in Figure 4, the strip 57 does not extend the full length of the brush strip, however, this has been found to be unnecessary for most service conditions. This leaves exposed the tab 61 which corresponds to the tab 21 of Figures 1 and 2 for securing the end closure of the brush seat to the brush roll body.

In this form of the invention the securing means for the brush strip is shorter and lighter than that shown in Figures 1 and 3 but do not give as finished an appearance.

The brush receiving indentations in the brush roll have been shown and described herein as having an L-shape in which the two walls forming the seat meet at substantially 90°. However, it is within the scope of the invention to vary this relation. It is only necessary that the brush seat be formed as an indentation in the periphery of the brush roll with a brush seated therein and wedged in position against the walls of the indentation by a readily accessible and removable clamping strip.

All forms of the invention provide a very convenient means for securing a strip type brush to an agitator body by a simple mechanical means which is readily removable for replacement of the brush. The attaching means are always exposed for adjustment or removal of the brush and are entirely within the periphery of the cylindrical brush roll so that they will never contact the surface being cleaned. The present construction has been found to be simple, economical and reliable in operation.

While I have illustrated and described the invention in considerable detail, it is to be understood that various changes may be made in the arrangement, proportion and construction of parts without departing from the spirit of the invention or the scope of the appended claims.

I claim:

1. A brush roll for cleaning tools comprising a cylindrical body portion having a longitudinally extending indentation formed therein, said indentation comprising a first wall portion which is substantially normal to a radius of said body portion, a second reversely curved wall portion which is substantially normal to said first wall portion and meeting said first wall portion to define an L-shaped seat for a brush strip, a brush strip comprising an elongated row of bristles secured to a backing member, said backing member being seated in said indentation at the junction of said wall portions and having a wide base portion resting on said first wall and partly underlying a part of said second wall, a deformation in said first wall portion forming a shoulder spaced from said backing member and said second wall portion, a clamping member having one portion engaging said backing member in spaced relation to said first wall portion and another portion engaging said shoulder, and means for drawing said clamping member toward said first wall portion to wedge said backing member against said wall portions at the junction thereof.

2. A brush roll for cleaning apparatus comprising a cylindrical body having an elongated indentation in the peripheral portion thereof, said indentation including two wall portions positioned in angular relation to each other, a

brush comprising a row of bristles carried by a base member, said base member being positioned in said indentation with spaced portions thereof engaging said wall portions, one of said wall portions having a shoulder formed therein in spaced relation to and facing said base member, a clamping member comprising an elongated spring plate having a plurality of spaced projecting spring tabs on one long edge thereof, the edge of said plate opposite said tabs engaging said shoulder and the said tabs engaging a portion of said base member spaced from both said wall portions, and means tensioning said spring plate in a manner to urge said tabs toward said one wall.

3. A brush roll for cleaning devices comprising a generally cylindrical body portion formed with an indented L-shaped seat defined by a first wall extending in a direction generally parallel to a radius of said body portion and a second wall generally normal to said radius of said body portion, a brush strip having bristles projecting outwardly of said cylindrical body portion and a back resting in said L-shaped seat engaging each of said walls, said second wall having an abutment portion in spaced relation to said brush back, a clamping plate having one edge engaging said brush back in spaced relation to said second wall and another edge engaging said abutment, and means urging said plate toward said second wall to wedge said brush back in said seat, said abutment portion and said clamping plate being a lesser distance from the axis of said cylindrical body portion than the unindented portions thereof.

4. A brush roll for cleaning devices comprising a generally cylindrical body portion formed with an elongated indentation defining a seat formed by a pair of angularly related walls, a brush strip having bristles projecting outwardly of said body portion and a back in said seat engaging each of said walls, one of said walls being formed with a shoulder in spaced relation to the other of said walls and said back, a clamping plate having one edge engaging said back in spaced relation to each of said walls and another edge engaging said shoulder, and a securing member engaging said one wall and said plate and biasing said plate toward said one wall to wedge said back in said seat, said plate and said shoulder and said securing member being at a lesser distance from the axis of said cylindrical body portion than the unindented portion thereof.

5. A brush roll for cleaning apparatus comprising a cylindrical body member formed with an elongated indentation facing outwardly of said body member and defined by a pair of angularly intersecting wall portions, one of said wall portions having a greater extent inwardly of the cylindrical body member than the other of said wall portions and being formed with a shoulder positioned in spaced relation to said other wall portion, a brush back seated in said indentation between said shoulder and said other wall portion and engaging each of said wall portions, brush bristles projecting from said brush back outwardly of said cylindrical body member, a clamping member engaging said shoulder and extending at an angle to said one wall portion and engaging said brush back in spaced relation to each of said wall portions, and means biasing said clamping member toward said one wall to wedge said brush back against each of said wall portions, said abutment and said clamping member being at a lesser distance from the center of

said cylindrical body member than the unin-dented portions thereof.

LOUIS E. SEGESMAN.
